UNITED STATES PATENT OFFICE.

BENJAMIN GLASMAN, OF BROOKLYN, NEW YORK.

DESIGN FOR A WATCH-CASE.

52,316.

Specification for Design.

Patented Aug. 27, 1918.

Application filed May 23, 1918. Serial No. 236,234. Term of patent 3½ years.

To all whom it may concern:

Be it known that I, BENJAMIN GLASMAN, a citizen of the United States, residing at the city of New York, borough of Brooklyn, in the county of Kings and State of New York, have invented a new, original, and ornamental Design for a Watch-Case, of which the following is a specification, reference being had to the accompanying drawing, forming part thereof.

Figure 1 is a plan view of a watch case showing my new design.

Fig. 2 is an edge view of the structure shown in Fig. 1.

I claim:

The ornamental design for a watch case as shown.

BENJAMIN GLASMAN.
